UNITED STATES PATENT OFFICE.

JOHN GREIVES AND JOHN H. BLEOO, OF PATERSON, NEW JERSEY.

UNDERGROUND ELECTRICAL CONDUCTOR.

SPECIFICATION forming part of Letters Patent No. 291,715, dated January 8, 1884.

Application filed May 11, 1883. (No model.)

To all whom it may concern:

Be it known that we, JOHN GREIVES and JOHN H. BLEOO, citizens of the United States, residing in the city of Paterson, in the county 5 of Passaic and State of New Jersey, have invented certain new and useful Improvements in Underground Electrical Conductors, fully described and represented in the following specification and the accompanying drawings, to forming a part of the same.

This invention relates to an improved system of laying electrical wires; and it consists, partly, in an improved means of obviating the effects of induction, and partly in an improved 15 well-hole and chamber, and in means for connecting the inclosing-pipes thereto.

The invention will be understood by reference to the annexed drawings, in which Figure 1 is a plan of a well-hole and its inclosed 20 chamber. Fig. 2 is a central vertical section of the same. Fig. 3 is a plan of the system applied to certain streets and blocks of ground. Fig. 4 is a perspective view of an inclosing-pipe containing a series of insulated wires. 25 Fig. 5 is a central vertical section of the pipes connecting two insulated chambers, II, an induction-wire, C, being shown connected with the ends of the pipe and with the envelopes of the conducting-wires. Fig. 6 shows the end 30 of the pipe B, indicated in Fig. 5, and exhibits the means of connecting with the induction-wire. Fig. 7 is a side view of one end of the pipe B, showing the wire C keyed into a hole in the pipe.

35 A A are the wires which are intended to be laid in the pipe B for conducting electrical currents, and in our system are coated separately with an insulating material.

B is a pipe or tube, preferably of metal, and 40 also lined with a coating of insulating material, as at E.

F is a coupling applied to screw-threads upon adjacent ends of the pipe (in Fig. 5) to join them together; but flanges and bolts may 45 be used, if preferred.

G is a drag-wire, placed inside the pipe B when the latter is laid and its separate sections coupled together, and the wires A A are introduced inside the pipe by the use of the

drag-wire, in the usual manner, at any subsequent time. 50

H is a metallic lining to a well-hole, placed at intervals along the line of the pipe B, to introduce and connect the wires A A at pleasure. 55

I is a wooden chamber, Fig. 2, or box, inserted within the lining H and separated therefrom by wooden cleats a a.

J J are sleeves large enough to fit very loosely around the pipe B, and are inserted 60 water-tight through coinciding holes in the walls of the lining H and chamber I, as by a screw-thread. The pipes B, when laid in the ground, are arranged to project through the sleeves J into the chamber I, and are made 65 water-tight in the joint through the sleeve by packing a gasket of suitable material therein, or pouring in melted lead and calking the same tight, as shown at c e in Figs. 2 and 5. The chamber I is shown in Figs. 1 and 2 as a rect- 70 angular box, which may be made of any size suitable for the operator to enter, and is provided with a removable cover, b, held in place by a bridge, d, inserted across the inside of the lining H, and provided with a set-screw, 75 e, to press down the lid, which latter is preferably fitted to the mouth of the box or chamber with a water-tight packing, as soft india-rubber. The lining H is provided with lugs f to hold the bridge d in place when in use, 80 and the well-hole and its lining are covered by a plate, K, at a level with the street.

With the construction described the pipes B are laid in sections between the separate well-holes, (a series of which is shown at III 85 in Fig. 3,) and after being properly united with a drag-wire inside them, and their extreme ends fitted to project into the chambers I, as desired, the packing e is applied around the pipes inside the respective sleeves J, and 90 the entire system of pipes and chambers becomes a water-tight and insulated receptacle for the conducting-wires A. This result is secured partly by making the chambers I of non-conducting material—as wood—and partly by 95 lining the same with a water-proof and insulating composition. Such a composition has already been patented to one of the inventors

hereof, and can be readily melted and applied in a fused state to the interior of the pipes B, as well as to the inside of the chamber I, rendering the latter impenetrable to moisture and 5 electrical currents. The wires A are laid loosely in the pipes B, and are connected, at the chambers I, by suitable binding-posts, g, or any form of switch-board that may be preferred. With this construction new wires can be introduced 10 into the system at any time and the connections altered as may be required.

At L in Figs. 4 and 5 is shown a construction for connecting service pipes and wires at any time after the pipes have been laid. At 15 intervals, say, of twenty-five feet nipples h are inserted in the pipes B and covered with water-tight caps M, lined, as well as the nipples, with the insulating composition. Such openings do not interfere with the operation of the 20 pipes and wires A, but are adapted at any time to permit the withdrawal of a single wire A and its connection with a telephone, lamp, motor, or other electrical apparatus at a given station. For this purpose the nipples h are 25 arranged upon the pipes B with reference to future or probable demands, and the service-pipes N, for protecting the service-wire, can be readily connected with the screw-nipple by a coupling, as shown at i.

30 Having thus set forth the nature and operation of the devices we employ in laying electrical conductors, we will describe the means shown in Figs. 5, 6, and 7 to obviate the effects of induction.

35 It is well known that a conducting-wire coated with insulating material may act as a Leyden jar, the insulating substance acting as the glass of the jar, and the electric charge of the conducting-wire inducing a charge of opposite electricity upon the outside of the coating. The wire and its non-conducting coating thus become a condenser, and a greater quantity of electricity must be put into it to charge 40 it with a given potential. The evil effects of this induction we obviate by providing a special conductor for the induced charge in the form of a naked wire at C, inside the pipe B, the wire C being connected at both ends to the ground, and the coatings of all the 45 closed wires A A being electrically connected with the same, as by connecting-strips D.

To connect the wire C, which, for convenience, we call the "induction-wire," with the ground most readily, we attach it by an electrical connection to both ends of the pipe B, which is made of metal, preferably, and, being laid directly in the ground, furnishes the ground-connection required. At the left end of Fig. 5 the wire C is shown fastened in a 50 binding-post, n, which is inserted through the insulating-lining E into the pipe B, while the opposite end of the induction-wire is shown inserted in a hole formed in the pipe inside the chamber I. To retain the wire in electrical 55 connection with the metallic surface of such hole, a wedge, o, may be inserted in the hole

beside the wire C, as shown in Fig. 7, and the latter be kept firmly in its place.

The connection D may be formed of a thin strip of sheet-copper, and may be applied to 70 the wire C and each wire A separately, as shown at the left side of Fig. 6, or be wrapped around a considerable number of the wires A, and led thence to the induction-wire.

It is obvious that this construction dis- 75 charges the induced electricity from the surface of the insulating-coatings around the wires A, and thus operates in the desired manner.

We are aware that it is not new to use a separate or naked wire to discharge induced electricity from an insulating-coating; but in the combinations heretofore devised each conductor has been furnished with a separate discharging-wire, or has been enveloped in a 85 sheet-metal coating in contact with its whole length. Our invention differs from these in employing only a single discharging-wire to free a considerable number of conductors from their induced electricity, which we accomplish by the connections D. It also differs in employing such connections only at intervals, instead of using a continuous contact, as in other inventions, and it was expressly invented to avoid the twisting of the dis- 90 charging-wire around and among the main conductors. By avoiding this feature, which is common to nearly all such discharging devices, we are enabled to insert fresh conductors in a conduit at any time, and simultaneously 95 utilize the discharging-wire previously provided. This is readily accomplished by adding suitable connections, D, at any convenient point, while the means for discharging as heretofore constructed have generally required provision in the process of manufacture, when they could be interwoven with the series of conductors permanently. In such construction additional conductors cannot be 100 combined with those already inserted in a 105 conduit, but require the same preparation with continuous discharging means, independent of those inserted in the conduit at 110 first.

By our construction the conductors are not 115 necessarily formed into a cable or mass at all, and additional wires can therefore be combined with them and the discharging-wire at any time.

We therefore claim our improvement as fol- 120 lows:

1. The means herein shown and described for discharging the induced electricity from the insulating-coatings of a series of electrical conducting-wires, consisting of the naked 125 wire C, laid parallel with the said series of conductors, and the connections D, united to the wire C at intervals and brought into contact with the several insulating-coatings, the whole being closed in a metallic pipe, and the 130 wire C being connected to the pipe at intervals, substantially as herein set forth.

2. The combination, with the well-hole lining H, of the wooden chamber I, insulated therein, substantially as shown and described.

3. The combination, with the well-hole lining H and wooden chamber I, of the sleeves J and the pipes B, secured therein, as and for the purpose set forth.

In testimony whereof we have hereunto set

our hands in the presence of two subscribing witnesses.

JOHN GREIVES.
J. H. BLEOO.
